UNITED STATES PATENT OFFICE.

BENT G. LARSON, OF JAMESTOWN, NORTH DAKOTA.

LADDER ATTACHMENT.

1,047,251.

Specification of Letters Patent.

Patented Dec. 17, 1912.

Application filed May 20, 1912. Serial No. 698,668.

To all whom it may concern:

Be it known that I, BENT G. LARSON, a citizen of the United States, residing at Jamestown, in the county of Stutsman and 5 State of North Dakota, have invented a new and useful Ladder Attachment, of which the following is a specification.

My invention relates to ladder attachments, for supporting paint pails and paint 10 brushes for painters' use; and the object is to provide an efficient device which may be readily adjusted at any desired height on a ladder and adapted to hold one or more paint pails and one or more paint 15 brushes above the paint pails, so that any paint dripping from the brush will drip into the pail; and as the device supports several pails and brushes, the operator may have the wall paint for a house in one pail and 20 the trimming paint in the other pail and apply both colors at a single placing of the ladder and a single trip up and down the same. Much time is thereby saved, and further time is saved by finding the brush 25 always ready for use and not submerged in the paint in the paint pail each time it has been idle while the other brush was in use. Time is also saved by being able to support the brushes without rubbing the 30 paint out of them, as the paint will drip from them into the pails.

In the accompanying drawing, Figure 1 is a front or outer side elevation of a portion of a ladder with my attachment adjusted on it and a paint pail and paint brush supported at one end thereof. Fig. 2 is an edge view of the ladder shown in Fig. 1 and the attachment on same. Fig. 3 is a top view of what is shown in Fig. 1.

Referring to the drawing by reference numerals, 1 designates the side bars and 2 the rungs of any form of ladder. Adapted to hang by hooks 3 upon either one of the rungs are two hangers 4, which extend downward about half way to the next rung below it, so as not to interfere with the regular use of the steps or rungs. Said hangers are 45 slidable on a horizontal bar 5, which bar rests against the outer inclined side of the ladder when the latter leans against the building to be painted. The ends of the bar 5 extend beyond the edges of the ladder and are each provided with a hook 6 for the support of the bail 7 of a paint pail suspended 50 as the pail 8; and adjacent said hook is a V-shaped gap or grip 9, in which

a paint brush 10 may be sufficiently squeezed to be held in such a position that paint dripping from it will drip into the pail supported on the hook.

To prevent tilting of the bar 5 when one paint pail is heavier than the other, or when only one pail is in use suspended at one end of the device, I secure the bar 5 to the ladder by additional means, which in the present embodiment of the invention consists of a standing bolt 11 fixed in each of the slideable arms 4; and upon each standing bolt a clamping arm 13 having a short sleeve 12 to guide it on the bolt; and rearward of each 70 clamping arm the bolt is provided with a partly compressed coil spring 14 with a washer 15 and a thumb-nut 16, by which latter two elements the tension of the spring is regulated.

In the operation or use of the device, the painter may suspend one or more paint pails and brushes on the device either before or after mounting the device on the ladder, in either case he walks up the ladder to the 80 desired height, places the hooks 3 upon one of the rungs, near the uprights of the ladder whether the ladder is wide or narrow; he then adjusts the clamps 13 and nuts 16 so as to hold the device with the necessary 85 firmness to the ladder. After the tension of the springs 14 is regulated for a certain ladder according to the thickness of its side bars, the nuts 16 remain unchanged and the 90 springs are simply compressed by the clamping arms in swinging the latter into and out of engagement with the side bars of the ladder in moving the device up or down on same.

What I claim is:

1. A ladder attachment comprising a bar adapted to extend across a ladder and extend beyond the edges thereof, each end of the bar provided with a hook adapted to receive the bail of a paint pail, and adjacent said hook a V-shaped notch adapted to hold paint brushes near above the suspended pail, and means for holding said bar to the ladder.

2. A ladder attachment comprising a bar 105 adapted to extend across a ladder and beyond the edges thereof, each end of the bar having a hook adapted to receive the bail of a paint pail, and adjacent such hook a V-shaped notch adapted to hold a paint 110 brush above the pail suspended from the hook, and means for holding the bar to the

2
ladder; said means comprising hooks adapted to take over the upper side of a rung of the ladder.

3. A ladder attachment comprising a bar adapted to be secured across a ladder and extend beyond the same, each end of the bar having a hook adapted to receive the bail of a paint pot, and a V-shaped gap adjacent thereto for holding a paint brush, and means for holding the bar to the ladder, said holding means comprising spring-closed clamps adapted to take over the side bars of the ladder, and means for regulating the tension of the springs of said clamps.

4. A ladder attachment comprising a bar adapted to be secured across a ladder and extend beyond the same, each end of the bar

having means for supporting a paint pail and a paint brush above the pail, and means for holding said bar to the ladder; said means consisting of two hangers slideable on the bar and provided with hooks adapted to take over the top of one of the rungs of the ladder, and clamps carried by the hangers for engaging the side bars of the ladder and pinch it against the crossing bar, whereby said bar forms one jaw of each clamp. 20 25

In testimony whereof I affix my signature, in presence of two witnesses.

BENT G. LARSON.
